UNITED STATES PATENT OFFICE.

DAVID E. CHANDLER AND JAY C. WILLIAMS, OF AURORA, ILLINOIS, AS-SIGNORS OF ONE-THIRD TO CHARLES HOWARD, OF SAME PLACE.

TWO-WHEELED VEHICLE.

SPECIFICATION forming part of Letters Patent No. 281,972, dated July 24, 1883.

Application filed June 20, 1883. (No model.)

To all whom it may concern:

Be it known that we, DAVID E. CHANDLER and JAY C. WILLIAMS, citizens of the United States, residing at Aurora, in the county of 5 Kane and State of Illinois, have invented new and useful Improvements in Two-Wheeled Vehicles, of which the following is a specification.

Our invention relates to that class of two-wheeled vehicles known as "driving-carts," 10 "road-carts," "dog-carts," and "sulkies."

The object of our present improvements is to provide means for maintaining the cart-body almost in a state of equilibrium by causing the body to rock upon a pivoted connection with 15 the springs and neutralizing said rocking motion, while at the same time checking lateral thrusts or jerks. These results we obtain by hanging the body between the springs upon a rock-rod or equivalent device having its bearings 20 in boxes upon the tops of the springs, over the axle, and by providing a central plate rigidly fastened to the cross-bar of the shafts, and extending back under the body through a loop and terminating shortly back 25 of said loop in a free end, and without fastening other than said loop, which confines it.

The improvements are specified in the claim and the construction illustrated in the accompanying drawings, in which—

30 Figure 1 represents a bottom view of a two-wheeled vehicle embracing our improvements; Fig. 2, a longitudinal vertical section, and Fig. 3 a detail, like letters indicating like parts.

35 A is the body; B, the wheels; C, the thills; D, the axle; E, side elliptic springs, and F the cross-bar of the thills or shafts. These are the parts common to the ordinary driving-cart.

40 The thills C are rigidly secured to the axle, and the body A is hinged between the springs E by means of a rod, G, running through the body A, beneath, from one side spring to the other. This rod is secured to the body either, 45 as shown in stay-posts b or in any suitable

manner; or it may, when the body is desired to hang high, be properly secured beneath it, and it has its bearings in boxes c, firmly secured centrally on the top of the springs; but the body need not necessarily be hung by a 50 rod, as brackets may project from the body, having cylindrical arm ends to enter the boxes on the springs; or the body may be hung between the springs, so as to have a pivot-bearing therein, in any suitable manner. Beneath 55 the front part of the body is a loop or staple, d, suitably secured, which is adapted to receive a strap or plate spring, I, which is clipped or bolted to the cross-bar F, or otherwise rigidly fastened at m to said cross-bar, 60 and extends back under the body through said loop or staple and terminates shortly back of said loop in a free end, n, without fastening other than its confinement by said loop. It prevents the pivoted body from tipping backward or forward, and works up and down with the main or side springs. The body being upon a pivot, the shafts will work 65 up and down, while the spring will slide back and forward under the body, and thus neutralize the "horse-jog."

We claim—

In a two-wheeled vehicle, the body A, pivotally hung between the side springs, and provided on its bottom with a loop, d, in combination with a centrally-arranged supporting plate-spring, I, rigidly fastened at one end to the cross-bar F, and its other end being free and passing through said loop and the side springs, substantially as and for the purpose 75 80 set forth.

In testimony whereof we have hereunto set our hands in the presence of two subscribing witnesses.

DAVID E. CHANDLER.
JAY C. WILLIAMS.
